United States Patent Office.

JOHN S. FULTON, OF GALLATIN, NEW YORK.

Letters Patent No. 103,866, dated June 7, 1870.

IMPROVED THRASHING-MACHINE.

The Schedule referred to in these Letters Patent and making part of the same.

To all whom it may concern:

Be it known that I, JOHN S. FULTON, of Gallatin, in the county of Columbia and State of New York, have invented a new and Improved Thrashing-Machine; and I do hereby declare that the following is a full, clear, and exact description thereof, which will enable others skilled in the art to make and use the same, reference being had to the accompanying drawing forming part of this specification, in which—

Figure 1 represents a plan or top view of my improved thrashing-machine, without the concave, which is shown in

Figure 2 in an inverted plan view.

Figures 3 and 4 are vertical transverse sections of the same, showing the concave, respectively, above and below the thrashing-cylinder.

Similar letters of reference indicate corresponding parts.

This invention relates to a new thrashing-machine, into which the straw is fed transversely, so that it will not in the least be injured or broken by the thrashing process, which will be very complete and satisfactory.

By leaving the straw unbroken, the value of the same is greatly increased, and, consequently, also the value of the machine.

The invention consists in the arrangement of the concave, which has a series of unbroken ribs and grooves, in which the straw can be rolled without being broken.

The invention also consists in making said ribs of unequal size, so as to gradually obtain the desired action, which, if sudden, might be injurious to the grain.

A in the drawing represents the frame of the machine. In it is hung the shaft of the horizontal thrashing-cylinder B, which is revolved by suitable machinery.

On the cylinder are arranged, at certain equal distances apart, projecting ribs *a a*, which are perfectly straight, smooth, and parallel with the axis of the cylinder.

On the frame is supported, either above the thrashing-cylinder, as in fig. 3, or below the same, the concave C, which is a block, with a concave inner face. In this concave face are arranged longitudinal ribs *b b*, as shown, the said ribs being also unbroken and smooth, as those of the cylinder.

The ribs in the concave are not all of equal size, but increase gradually toward the middle, as is clearly shown in fig. 1, and again from the middle toward the outer or discharge end. In the middle is a separate section of equal-sized ribs.

The several (three or more) sections are, as in fig. 2, a small space apart.

The straw is fed transversely, that is to say, parallel with the ribs, and the gradually-increasing ribs of the first section roll out the grain gradually.

In the space between the first and second sections the ears can be changed, so that they will not always be in the same position, and the second section, consisting of smaller ribs, will separate almost all grain left by the first section.

The third section perfects the operation gradually and thoroughly.

If the concave is used below the cylinder, it is placed upon springs *c c*, which hold it against the cylinder. In that case a cap, D, should be placed over the cylinder, as shown.

The grain and straw are discharged from the machine in good order, causing no loss of the products of the farms.

Having thus described my invention,

I claim as new and desire to secure by Letters Patent—

1. The cylinder B having longitudinal smooth-faced ribs *a a*, parallel to its axis, in combination with a concave, having corresponding longitudinal smooth-faced ribs thereon, so as to roll the straw with as little as possible of rubbing-friction, to avoid cracking the grain or breaking the straw, all as set forth.

2. A concave, C, of a thrashing-machine, having longitudinal ribs thereon, running at right angles to the plane of rotation of the cylinder, and arranged in three sets, the first having ribs increasing in size toward the center, the middle having ribs of uniform size, and the last set increasing in size to the outlet, all as shown and described.

JOHN S. FULTON.
